UNITED STATES PATENT OFFICE.

IGOR S. BOBROVSKY, OF RIVERDALE-ON-HUDSON, NEW YORK.

ELECTRICAL REPRODUCER.

Application filed August 28, 1926. Serial No. 132,096.

This invention relates to electrical reproducers for phonographs, and has for its object the production of an efficient sound reproducing mechanism, wherein the magnetic flux in the pole pieces varies constantly with variations of the armature and follower or needle.

Another object of my invention includes the production of a construction which is simple in construction and reliable and effective in operation.

Other objects will appear hereinafter, and I attain these objects by the construction illustrated in the accompanying drawings, in which

Fig. 1 is a plan view of a construction which embodies the principles of my invention.

Fig. 2 is a plan view with the cover removed.

Fig. 3 is a sectional view taken on the line 3—3 of Fig. 1.

Fig. 4 is a view taken on the line 4—4 of Fig. 2, and

Fig. 5 is a view of the armature and pole pieces.

The same numerals refer to like parts throughout the several views.

In a preferred form of construction, to which, however, I do not desire to be understood as limiting myself otherwise than as stated in the appended claims, I provide two permanent magnets 10 and 11. These magnets are preferably semi-circular in shape and are placed with their like poles opposite pole pieces 12 and 13. These pole pieces are secured to the shell or casing 14, by any suitable means as screws 15 and 16. For convenience, pole piece 12 may be regarded as the north pole and pole piece 13 as the south pole. The north pole is longer than the south pole, and it carries the magnetic coil 17 affixed thereon at right angles to the axial line of the pole. The respective ends 19 and 20 of the coil wire are secured to the lead wires 21 and 22 by binding pieces 23 and 24. These pieces are carried on disk 25 of insulating material.

The south pole carries the armature 26, which is pivotally saddled on the pole by the

pivot saddle 27, so as to swing back and forth in response to the motion of the record needle 28, as it follows the grooves in the record (not shown). The action of the armature causes the distance between the armature tail 29 and the north pole to vary, and consequently the magnetic flux therein and in coil 17 varies also. Any suitable means as spring 30, normally holds the tail 29 and the north pole spaced in proper relation. A cap 31 protects the construction, and a thumb screw 32 holds the needle secure. The magnetic properties of the magnet pieces must be permanent, and I use for this purpose cobalt steel as best suited for my purpose.

While I have shown and described a specific construction, I do not thereby desire to be understood as having thus limited myself unnecessarily.

What I claim, therefore, as new and useful, and desire to secure by Letters Patent is:

1. An electric reproducer comprising a pair of permanent magnets, pole pieces arranged between said magnets, a coil carried by one of said pole pieces, and a saddle piece pivotally mounted on the other of said pole pieces, said saddle piece carrying a needle and having a tail piece extending to the other of said pole pieces.

2. An electric reproducer comprising a pair of permanent magnets, pole pieces arranged between said magnets, a coil carried by one of said pole pieces, and a saddle piece pivotally mounted on the other of said pole pieces, said saddle pieces carrying a needle and having a tail piece extending to the other of said pole pieces, and means for controlling the position of said saddle piece.

3. An electric reproducer comprising two permanent semi-circular magnets, a case for holding said magnets with their like poles opposite each other, a pole piece between the north pole of the magnets and a pole piece between the south pole of said magnets, a coil carried by said north pole and a saddle piece carried by said south pole.

4. An electric reproducer comprising two permanent semi-circular magnets, a case for holding said magnets with their like poles

opposite each other, a pole piece between the north pole of the magnets and a pole piece between the south pole of said magnets, a coil carried by said north pole and a saddle piece carried by said south pole, said saddle piece having a needle for following the grooves in a phonograph record and a tail

piece extending over a portion of the north 10 pole, and means for controlling the position of the saddle piece.

In testimony whereof I have hereunto set my hand on this 23rd day of August, A. D., 1926.

IGOR S. BOBROVSKY.
